UNITED STATES PATENT OFFICE.

CHARLES J. RYBERG, OF CHICAGO, ILLINOIS, ASSIGNOR TO NATIONAL CHRONOGRAPH COMPANY, OF CHICAGO, ILLINOIS, A CORPORATION OF ILLINOIS.

ELECTRICALLY-OPERATED SIGNALING AND RECORDING DEVICE.

1,317,321.

Specification of Letters Patent.

Patented Sept. 30, 1919.

Application filed December 18, 1915. Serial No. 67,611.

To all whom it may concern:

Be it known that I, CHARLES J. RYBERG, a citizen of the United States, and a resident of Chicago, in the county of Cook and 5 State of Illinois, have invented certain new and useful Improvements in Electrically-Operated Signaling and Recording Devices, of which the following is a specification, reference being had to the accompanying 10 drawings.

My invention relates to electric signaling devices which are also provided with recording mechanism for registering the time when the signals are given, and in the embodiment of my invention shown and described in this application it has particularly to do with locks for the doors, windows or other openings of a building, which must be closed and secured to prevent unauthorized entrance thereto.

There has long been a demand for an apparatus which would record the time when a store or other place of business was unlocked in the morning and locked up at 25 night, and it has heretofore been proposed to supply this demand by providing one or more of the doors with a lock having associated with it on the door, recording mechanism which would register the time when 30 such lock was operated either to lock or to unlock the door. In prior constructions this necessitated the application to the door of a special lock in addition to the ordinary lock, and also of recording mechanism operated by such special lock. Devices of this character have not, however, been satisfactory, not only because they are bulky and unsightly when applied to a door, but also because the necessity of applying them to 35 the door requires that the parts be small and therefore more or less delicate in construction, so that they are frequently damaged by the shutting or slamming of the door. Moreover, in such prior devices the 40 chronometric mechanism necessarily employed is so placed as to be subject to temperature variations, and therefore its accuracy is unfavorably affected. A further objection to the use of a supplemental registering lock is that the employee whose duty it is to attend the locking up or unlocking 45 the place, may, if he wishes to deceive the proprietor, operate the special lock at one

time, and the ordinary lock at another time, and the registering device will indicate only 55 the time of the operation of the special lock. For example, if the employee is supposed to open the door at seven o'clock in the morning, he may unlock the special lock at that hour, leaving the door locked by the 60 ordinary lock, attend to personal errands in the interval before other employees are due to arrive, and then return and unlock the ordinary lock in time for their admission, and the employer would be given to 65 believe by the recording device that the store had been opened at seven o'clock.

The objects of my invention are:—

First, to avoid the objections above mentioned by providing a lock-operated recording device adapted to be operated by an ordinary door lock without changing such lock in any particular;

Second, to provide a recording device for locks which may be placed at any desired 75 point without regard to the location of the lock, as, for example, in the office or in the home of the proprietor of the store, so that it may be made as large and strong as may be necessary, and may be fully protected 80 against tampering or injury;

Third, to provide a recording or signaling device with operating mechanism actuated by the projection or retraction of the bolt of an ordinary lock, to register the instant 85 at which such bolt is moved;

Fourth, to provide registering or signaling apparatus with operating mechanism which is normally unaffected by the projection or retraction of a second bolt, which 90 may be the usual latch-bolt of a lock, when the key-bolt remains retracted, but is actuated by movement of the second or latch-bolt while the door remains locked by the projection of the key-bolt, to operate 95 the recording or signaling apparatus. By this means a record is made whenever the latch-bolt is retracted or projected by the turning of the door-knob, or by such other means as may be characteristic of the lock, 100 so that the apparatus serves as a watchman's time recorder, as it records the time whenever, in making his rounds, the watchman turns the door-knob or otherwise withdraws the latch or other second bolt to try 105 the door. By making the second bolt in-

operative when the key-bolt is in its retracted position, the usual latch may well be used for this purpose as the recording mechanism is not operative while the store 5 remains unlocked during business hours;

Fifth, to provide a signaling device connected with the main door lock and with other suitable locks applied to other doors and windows, which, when the key-bolt is 10 projected in locking the main door, will indicate whether or not all the other doors and windows have been properly secured. I use the term "main door" to indicate the door used by the person who opens the place in 15 the morning and closes up at night, but generically it may be understood to mean any door whose lock operates the registering apparatus.

In addition to these principal objects of 20 my invention, it is also my object to provide various improvements in the construction and operation of electrically-operated signaling mechanism, which will be specifically hereinafter pointed out.

25 In the drawings I have illustrated one form in which my invention may be embodied, and shall now particularly describe the apparatus so illustrated, but I wish it to be understood that the apparatus so shown 30 and described is merely one of various ways in which the objects of my invention may be realized. The claims hereinafter made are accordingly to be construed generically, and are not to be limited to the specific construction shown and described, except in so far as 35 they are particularly directed to the details of such construction.

In the accompanying drawings,—

Figure 1 is a side elevation of the recording mechanism which forms a part of the 40 complete signaling apparatus, the cover or housing being removed;

Fig. 2 is a diagram illustrating the electric circuits;

45 Fig. 3 is an elevation of the recording apparatus, taken at right angles to the view shown in Fig. 1, the cover being in section;

Fig. 4 is a plan view of the recording apparatus;

50 Fig. 5 is a view of one of the record form sheets used on the recording apparatus;

Fig. 6 is a sectional view of part of the recording apparatus, taken on line 6—6 of 55 Fig. 3, the record cylinder and its supporting shaft being shown in a changed position;

Fig. 7 is a plan view of the dial plate of the chronometer showing the hour and minute hands, part of the frame of the recording apparatus being shown in section;

Fig. 8 is a vertical section, through a part of the chronometer, on line 8—8 of Fig. 7;

Fig. 9 is an enlarged sectional view showing the manner in which the record cylin-

der is operatively connected with the screw-threaded shaft on which it is mounted;

Fig. 10 is a view of the inner face of the keeper-plate and the parts carried thereby, the housing of certain of said parts being 70 shown in section;

Fig. 11 is a sectional view on line 11—11 of Fig. 10, showing the various levers and contacts by the operation of which registrations are effected;

Fig. 12 is a sectional view on line 12—12 of Fig. 11;

Fig. 13 is a view of one of the fasteners for securing windows, doors, or other openings, arranged to coöperate with the main door lock to operate an alarm signal when the place is not properly locked up, as hereinbefore suggested;

Fig. 14 is an edge view of the parts shown in Fig. 13, looking to the left;

Figs. 15, 16, and 17, are views similar to Figs. 10, 11, and 12, respectively, showing certain modifications; and Fig. 18 is a view partly in section showing a lock associated with the keeper plate and the parts carried 90 thereby, the key and latch bolts being shown in locking position.

The apparatus illustrated in the accompanying drawings comprises three main instrumentalities which coöperate in accomplishing the principal end desired—to-wit, insuring that the place in connection with which the apparatus is used has been properly locked up, and registering the time when the place is locked or unlocked. One 100

of these instrumentalities is a chronograph, or a recording apparatus which includes a chronometer, or equivalent time-measuring device, means associated with such chronometer to receive and preserve records made 105 from time to time in such manner as to show the time when such records were made, and mechanism arranged to be automatically operated by certain mechanism associated with and operated by the key-bolt or latch-bolt of the main door lock, which latter mechanism constitutes one of the other instrumentalities referred to, so that the operation of such key or latch bolts will actuate such recording mechanism so as to 110 make a record on the record sheet thereof. The other of the three instrumentalities mentioned is suitable bolting apparatus for securing the windows and doors other than the main door, and acting through suitable 115 switches and electric circuits to sound an alarm when the main door is locked and such other windows and doors have not been properly secured.

With this brief outline of the chief parts 125 of the apparatus considered as a whole, I shall now describe specifically the device illustrated in the drawings.

The recording apparatus.—The recording apparatus comprises a base 20, which is pref-

erably circular in shape and is made of any suitable material. It is preferably provided with a ledge 21 at its upper margin which forms a support for a dome-shaped housing 5 or cover 22, as best shown in Fig. 3. This cover is of such size and shape as to inclose the apparatus mounted on the base, and is arranged to be secured and locked to the base by providing it with downwardly-projecting hooks 23, preferably at diametrically opposite points adjacent to its lower margin, and with a laterally-projecting perforated lug 24 at a point about ninety degrees from the hooks 23. The hooks 23 are adapted to 10 enter slots 25 provided in the ledge 21, as shown in Fig. 4, the arrangement being such that after said hooks enter said slots, by turning the cover slightly, said hooks may be caused to engage suitable portions of the 15 base, the construction and operation being similar to that of a bayonet joint. The lug 24 is adapted to coöperate with a perforated lug 26 carried by the base, as shown in Figs. 1, 3 and 4, being arranged to register therewith when the hooks 23 are in engagement with the base. By then passing the hasp of a padlock or other locking device through the registering perforations of said lugs 24-26, the cover is locked to the base, and 20 not only protects the recording mechanism from being tampered with, but may be used as a means of lifting and carrying the apparatus from place to place. The latter operation is facilitated by providing the cover 25 with a handle 27 at the top, as shown in Fig. 3.

28 indicates a chronometer which is mounted on the base, as shown in Fig. 1, and is provided with an ordinary clock dial 29. 30 indicates the hour hand of the chronometer, which preferably extends entirely across the face of the dial and is provided at one end with an upwardly-projecting pin 31, tapered at its upper end to a point, and 35 at its other end is provided with a counter-balancing weight 32 to offset the weight of the connecting-rod hereinafter mentioned. 33 indicates a minute hand, which is preferably T-shaped, having arms 34 extending 40 in opposite directions from its pivotal point and at right angles to the main portion of the minute hand. These arms are provided with knobs 35 by means of which the minute hand may readily be rotated when it is 45 necessary to set the chronometer. The chronometer is preferably operated by a spring in the usual way, the spring being adapted to operate the chronometer for a period of approximately eight days. The 50 function of the chronometer is to regularly rotate a drum or cylinder 36 which carries a record sheet or blank 37 upon which registrations are made when the locking devices are operated from time to time. The 55 manner in which this drum is mounted and its mode of operation will be best understood by reference to Figs. 1 and 6. As shown in Fig. 6, the drum is provided with a central sleeve 38 which forms a passage 70 through the drum at its axis for the reception of a shaft 39 which fits smoothly in said sleeve. This shaft, preferably at its intermediate portion only, is provided with screw-threads 40, and on one surface—preferably that surface which is uppermost 75 when it is in operative position—the drum is provided with a lever 41 mounted between its ends upon a pivot 42, as best shown in Fig. 4. The lever 41 is disposed tangentially to the valleys of the screw-threads in the shaft 39, with which it engages in the manner shown in the latter figure. To minimize friction, said lever is provided with an anti-friction roller 43 mounted on a pin 44, said roller being 80 adapted to engage the screw-threaded portion 40, as shown in Fig. 9. A spring 45 connected with the drum and with the lever 41 normally holds the roller 43 in operative position. A stop 45^a engages the lever 41 85 so as to prevent the inner face of the roller 43 from frictionally engaging the shaft 39. The outer ends of the lever 41 are preferably provided with knobs 46 by means of which the lever may conveniently be swung upon 90 its pivot to disengage the roller 43 from the shaft 39 to permit the drum to be moved freely longitudinally of said shaft. It will be apparent from the foregoing description that the shaft 39 being stationary, when the 95 drum 36 is rotated in one direction, it will move toward one end of the shaft, and when rotated in the opposite direction, it will move toward the opposite end of the shaft. Normally said shaft stands in a vertical position, as shown in Fig. 1, when the 100 drum is arranged to rotate with the hour hand 30 of the chronometer. A right-hand screw-thread 40 is used so that when the drum rotates in the manner indicated, it will 105 gradually move down on the shaft 39. Thus the effect of gravity is to assist in rotating the drum. For connecting up the drum with the hour hand, the drum is provided with a second sleeve 47 forming a passage 110 through the drum which is at the same radial distance from the axis of the drum as the pin 31 is from the axis of the hour hand, these two axes being coincident. Thus by turning the drum to the proper position, 115 the pin 31 may be brought into line with the passage through the sleeve 47, so that a connecting-rod 48 may be passed through said sleeve into engagement with the pin 31 in the manner shown in Fig. 1. For this 120 purpose, a tubular rod is used having a head 49 by which it may easily be handled. The rod 48 slides freely through the sleeve 47 and consequently permits vertical movement 125 of the drum, meanwhile causing it to rotate 130

with the hour hand of the chronometer. Said rod may readily be withdrawn as occasion requires.

The shaft 39 is supported from its upper end, and is so mounted that it may be held in a vertical position, as shown in Fig. 1, or in a horizontal position, as shown in Fig. 6. The first of these positions is that which it occupies when the apparatus is in condition for operation, the latter position being that to which the shaft is turned when a record sheet is to be applied to or removed from the drum, or when the drum itself is to be taken off the shaft. The construction by which this is effected is best shown in Figs. 1, 4 and 6. As best shown in Fig. 6, I provide an L-shaped standard 50, which is secured upon the base 20 in any suitable way, so that it is held rigidly in position. This standard is best made of channel-shaped metal, bent intermediately at an angle of ninety degrees. The upper or horizontal arm of said standard terminates in line with the axis of the hour hand 30, and the upper end of the shaft 39 is pivotally connected to this arm of the standard by trunnions 51 which engage the hub 52 of a lever 53 fitted upon the upper end of said shaft. The material between the flanges of the channel-iron is cut away to permit the lever 53 to swing freely upon said trunnions, as shown in Fig. 6. The lever 53 is arranged to project toward the vertical arm of the standard 50 when the shaft 39 is in its vertical position, and is provided with an angular lug 54 having a slot 55 which is adapted to receive a sliding catch 56. This catch is mounted to slide longitudinally upon the horizontal portion of the standard 50, being mounted upon screws 57 which pass through a slot 58 in said catch, as shown in Fig. 6. At its outer end the locking catch 56 has a knob 59 by which it may be moved longitudinally, and it is impelled toward the shaft 39 by means of a spring 60 secured to the upright portion of the standard 50, as shown in Fig. 6. At a portion adjacent to the inner end of the locking catch 56 the web of the standard is cut away as shown at 61 in Fig. 6 for the passage of the lug 54, the arrangement being such that when the lever 53 is in its horizontal position, as shown in Fig. 1, the slot 55 is adapted to register with the inner end of the catch 56, which then enters it and holds the lever 53 firmly in its horizontal position, thereby locking the shaft 39 in its vertical position. The shaft 39 is held in its horizontal position, shown in Fig. 6, by means of a latch 62 mounted upon a pivot 63 near the free end of the horizontal portion of the standard 50 and adapted to engage a lug 64 projecting from the hub 52 at the side thereof opposite the lever 53, as shown. The free end of the latch 62 is preferably provided with a knob 65

by which it may be lifted to disengage the lug 64 and release the shaft 39. Obviously, when the parts are in the position shown in Fig. 6, the latch 62 holds the shaft 39 in its horizontal position, but by lifting the latch to disengage it from the lug 64, the shaft is permitted to swing down into its vertical position, carrying with it the drum 36. The momentum of the shaft and drum when released is sufficient to carry the lever 53 to its horizontal position and cause the catch 56 to engage the notch 55 and automatically lock the shaft in its normal position. This is facilitated by beveling the lug 54 as shown in Fig. 6. The latch 62 is preferably provided with lugs 66 at opposite sides of its pivot to limit its movement in one direction or the other.

The record sheet 37 fitted upon the cylinder 36 is preferably a transparent sheet of paper of suitable shape, ruled in the manner shown in Figs. 1 and 5, one end margin being left blank and gummed so that the blank may readily be applied to the cylinder. The sheet does not bear directly on the metal of the cylinder, a sheet of carbon paper 66^a being placed under the record sheet and a rubber platen 66^b being fitted upon the cylinder between the metal and the carbon sheet so that a proper printing surface is provided, the arrangement being such that when the impression sheet is struck by a key or other record making device, the carbon sheet makes an imprint on the under surface of the record sheet, which is visible through such sheet owing to its being transparent. This construction is desirable because it avoids the necessity of providing inking apparatus and makes a record which is visible without removing the record sheet from the cylinder. Preferably what is the lower margin of the cylinder when in operative position is provided with a flange 67 which projects radially to a slight extent to protect the platen and record sheet, as best shown in Fig. 6. As illustrated in Fig. 5, the record sheet is divided into fourteen horizontal divisions or zones, which are alternately ruled and plain. These zones are each as wide as the distance between threads of the shaft 39, so that the width of each zone measures one complete rotation of the cylinder, and consequently twelve hours of time. The ruled zones preferably represent time from noon to midnight, while the unruled zones represent time from midnight to noon, two adjacent zones taken together representing a full day of twenty-four hours. It follows that there being fourteen zones altogether, the record sheet as a whole represents a week, and it is preferably marked to indicate the different days of the week, as shown in Fig. 5. It is also ruled vertically in twelve principal subdivisions to indicate the several hours of the day, these rulings being prop-

erly numbered, and it may also be subdivided to indicate further subdivisions of time. It will be apparent from the foregoing that the record sheet being properly placed on the cylinder 36, and the latter being connected to the chronometer, the moment during the week when any imprint was made on the record sheet is apparent at a glance.

10 The making of records upon the record blank is effected by means of levers or hammers bearing characters or types adapted to strike the record sheet with sufficient force to cause the impression sheet to correspondingly mark the record sheet. In the apparatus illustrated—which, as has been explained, is operated to make a record not only by the operation of the key-bolt, but also, while the door is locked, by the movement of the latch-bolt—I employ two of such levers, which are operatively associated, respectively, with the key-bolt and the latch-bolt of the main door lock, as will be hereinafter described. These type levers 15 are similar in some respects to the type levers of a typewriting machine in that they are pivotally mounted and are arranged to move quickly and forcibly on their operative stroke so as to strike the record sheet on the platen sharply. Their striking faces are provided with type which will print the desired letter or symbol on the record sheet, and preferably I provide one of the type levers with a triangular type and the other 20 with a type which will print a vertical line. The triangular type is arranged so that its base is horizontal, and the parts are adjusted so that the proper time registration is shown at its apex. These type levers, which 25 are numbered 68—69, are best shown in Figs. 3 and 4. As shown in Fig. 3, they are disposed horizontally, being mounted upon pivots 70—71, respectively, which are held in position by adjustable screws 72—73 mounted 30 in frames 74—75 at opposite sides of the standard 50 and firmly secured thereto. By this construction the type levers may be adjusted vertically to a slight extent. As best shown in Fig. 4, the pivots of the type levers 35 68—69 are placed near their outer ends, which are provided with slots 76—77. The opposite ends of said type levers are bent, or otherwise fashioned so that they project inwardly, *i. e.*, toward the standard 50, the type 40 78—79 being mounted on the faces of such angular portions of the type levers so that when the levers are swung toward the standard 50 the type are adapted to strike the platen. In order to permit this, the 45 standard 50 is provided with a suitable opening 80, as shown in Fig. 3.

The type levers are operated by means of vertically-disposed arms 81—82 connected, respectively to armatures 83—84 of electromagnets 85—86 suitably secured upon the

base 20, as shown in Figs. 1 and 3. The armatures 83—84 are pivotally mounted in any suitable way, as by means of pivot-screws 87, so that they swing toward and from their respective electromagnets, the return movement, when the magnets are deenergized, being effected by means of springs 88 shown in Figs. 1 and 3. In the construction shown, these springs are connected to the armatures below the pivots thereof, and to rotatable adjusting-pins 89, which are normally secured against rotation by set-screws 90. Any other suitable construction for the purpose may, however, be employed. 91 indicates stop-screws for limiting the extent to which the armatures may move away from their respective electromagnets. The upper ends of the arms 81—82 fit, respectively, in the slots 76—77 of the type levers 68—69, and the parts are arranged so that when one or the other of the electromagnets is energized and attracts its armature, the arm connected with such armature will be moved quickly so as to throw the corresponding type lever forcibly toward the platen, thereby making a record. 95 The two type levers are adjusted with reference to each other so that they do not interfere. By this construction I secure a very sharp, quick action of the type levers, with the result that a well-defined imprint is 90 made on the record sheet.

92 indicates a bracket, which is adjustably mounted on the standard 50 so as to be moved vertically thereupon, said standard having a slot 93 which receives a lug 94 100 projecting from said bracket, as shown in Fig. 6. A screw 95 projects through said slot into the bracket 92, and also through a plate 96 which is fitted against the outer face of the standard 50, the bracket 92 being 105 mounted on its inner face, so that the parts operate as a clamp to secure the bracket in its different positions of adjustment. Said bracket carries a screw 97 which projects upward in such position that it may be 110 brought into engagement with the cylinder 36 when the latter is in its normal or operative position. The purpose of this bracket and the parts associated therewith is to provide for accurately setting the cylinder at 115 the proper hour and day when starting its operation, the bracket being lowered to near the bottom of the standard 50 when this has been accomplished. As shown in Fig. 3, the standard 50 is preferably ruled to 120 indicate the days of the week and the halves of each day, and the plate 96 is provided with a pointer 98 by means of which the position of the screw 97 may be accurately adjusted. By then lowering the cylinder 36 125 until it rests upon the screw 97 and setting the chronometer, the record sheet is properly set so that any registrations made thereafter are correctly entered.

Assuming that the recording apparatus is 130

put into use at the beginning of the week, the cylinder 36 is adjusted to the proper point near the upper end of the shaft 39, which is best done when the shaft is in its horizontal position shown in Fig. 6, although the cylinder may be adjusted when the shaft is in its vertical position. Assuming that the record sheet has been properly placed upon the cylinder, the cylinder is connected with the chronometer by means of the rod 48 in the manner described, whereupon the cylinder is rotated with the chronometer, gradually descending until at the end of the week it reaches its lowermost position. The cylinder may be inspected at any time, and the record sheet removed or replaced at such intervals as may be desired. When this is to be done, the sliding catch 56 is drawn out of engagement with the arm 53, and the shaft 39 is then swung to its horizontal position. When this is to be done near the end of the week—that is to say, when the cylinder has approached the lower end of the shaft 39, the cylinder is first run up on the shaft before the latter is swung to its horizontal position, to prevent the cylinder from striking the chronometer. Of course the rod 48 must be withdrawn before the shaft 39 is free to swing. The cylinder may be moved lengthwise of the shaft either by rotating it, or by swinging the lever 41 out of engagement with the threads of the shaft 39, which permits the cylinder to be moved freely lengthwise of the shaft, or to be withdrawn from the shaft altogether. With the parts in the position shown in Fig. 6, the record sheet may be removed and another one put in its place, after which by lifting the latch 65 out of engagement with the lug 64, the shaft 39 may be returned to its vertical position, and the cylinder 36 again connected to the chronometer by the rod 48. By means of the bracket 92 the position of the cylinder is then properly adjusted, after which said bracket is dropped out of the way, and the recording device is ready for operation.

The actuating mechanism for the recording apparatus.—From the foregoing description, it will be apparent that the recording apparatus may be actuated by properly energizing one or the other of the electromagnets 85—86, one of which is appropriated to the key-bolt and the other to the latch-bolt of the main door lock. As has been explained, so far as the lock mechanism, including the key-bolt and the latch-bolt, itself, is concerned, it may be of any ordinary construction, as my invention does not require any special construction of those parts. But to facilitate a clear understanding of my invention, in Fig. 18 I have illustrated a simple form of lock that is well adapted for use. In said figure, 184 indicates the usual key-operated bolt, and 185 indicates

the usual latch-operated bolt, the latter being normally held projected by a spring 186, in the ordinary way. The necessary electric switches by which the circuits through the electromagnets are established or broken, are associated with the keeper required for receiving the key-bolt 184 and the latch-bolt 185 of the lock, and these parts are illustrated in Figs. 18, 10 and 11. The electric circuits are shown in Fig. 2. Referring now to said figures, 99 indicates the usual keeper-plate—that is to say, a plate having the usual rectangular openings for the reception of the key-bolt 184 and the latch-bolt 185 of the lock, and preferably a beveled portion 100 to press back the latch-bolt when the door is closed so that the door may close without a shock. In the construction shown, the upper opening is intended for the key-bolt and the lower one for the latch-bolt. The key-bolt opening is normally covered from the inside by a plate 101 which is provided with suitable arms 102—103 by which it is connected to a pivot 104, suitably mounted in the plate 99 above the key-bolt opening, as shown in Figs. 10 and 18. A spring 105 serves to hold the plate 101 normally in engagement with the keeper-plate 99. Preferably, the plate 101 is arranged to fit closely in the key-bolt opening, it being provided with any suitable means to prevent it from moving entirely through said opening, as by providing it with a lip 101^a projecting at one side or end of the opening, as shown in Fig. 18 and as indicated by dotted lines in Fig. 10. 106 indicates a plate, which is secured to the keeper-plate 99 and stands at right angles therewith, as shown in Figs. 10 and 18, forming a part of a box-like housing which incloses certain parts hereinafter described. The pivot 104 projects through said plate 106 and carries an arm 107, as shown in Fig. 11. 108 indicates a plate, similar to plate 101, which covers the latch-bolt opening, and is connected by arms 109—110 with a pivot 111 similar to the pivot 104. 112 indicates a spring for holding the plate 108 in position over the latch-bolt opening. The pivot 111 also projects through the plate 106, and carries an arm 113 similar to the arm 107, as shown in Figs. 10 and 11. 114 indicates a lever which, generally speaking, is of bell-crank form. Said lever is pivoted intermediately, at 115, so that it rocks in a plane parallel with that of the plate 106. In the illustrated construction one of the arms 116 of said lever 114 projects upwardly and is curved around the arm 107, the end of the latter projecting into a notch 117 provided in the arm 116, as shown in Fig. 11, the arrangement being such that when the arm 107 is swung to the right it rocks the lever 114 in a clockwise direction about its pivot. 130

When this occurs, the arm 116 is adapted to engage a spring-contact 118 supported near the plate 106, but insulated therefrom. 119 indicates a wire connecting with the 5 spring-contact 118. 120 indicates the other principal arm of the lever 114, which are carries two lips, numbered 121 and 122, respectively. When the lever 114 is rocked, the lip 121 is adapted to make passing contact with a spring-brush 123 supported near the plate 106, but insulated therefrom, and having a connecting-wire 124. The lip 122 projects into engagement with an arm 125 of a four-armed lever 126 mounted on a 10 pivot 127 adjacent to the pivot 112 of the plate 108 associated with the latch-bolt opening. 128 indicates another arm of said lever 126, which, when said lever is in the position shown in Fig. 11, lies out of, but 15 adjacent to, the path of the arm 113, so that said arm 113 may then swing without engaging the arm 128. This position is maintained so long as the lever 114 is in the position shown in Fig. 11 which is the position it occupies so long as the key-bolt is 20 retracted and the door is unlocked. While this condition obtains, it will be apparent, therefore, that the latch-bolt may move into and out of its opening in the keeper-plate, 25 and consequently swing the plate 108 back and forth, thereby rocking the arm 113 in one direction or the other, without affecting the lever 126. When, however, the key-bolt is projected into its opening in the keeper, 30 it swings the plate 101 so as to rock the arm 107 to the right, thereby correspondingly swinging the bell-crank lever 114 and moving the lip 122 to the left. This permits the arm 128 to swing toward the pivot 112 35 of the arm 113, under the action of a spring 129 shown in Fig. 11, far enough so that when the arm 113 is rocked it will rock the lever 126 upon its pivot. This occurs whenever the latch-bolt is moved into or out of 40 its opening in the keeper-plate. From the foregoing description it will be seen, therefore, that so long as the door is unlocked, the latch-bolt may be moved into and out of its socket without rocking the lever 126, 45 but that as soon as the door is locked, the lever 126 will be rocked whenever the latch-bolt is moved into or out of its socket. The lever 126 is provided with another arm 130, which is adapted to make passing contact 50 with a spring-brush 131, supported by, but insulated from, the plate 106, and connected to a wire 132. Preferably, the spring-contacts 115, 118, 123, 127, and 131 are all mounted upon a plate 133, of insulating material, which cooperates with the plate 106 to make a box-like inclosure for the parts described,—the other sides of the box being inclosed in any suitable way. 134 indicates a conductor which connects levers 114 and 55 126, this being preferably a strip of brass which is secured to the plate 133 and is connected to the pivots 115 and 127, as indicated by dotted lines in Fig. 11. 135 indicates a wire connecting with the conductor 134. The circuits of the parts thus far described are best shown in Fig. 2. As therin shown, the wire 119 leading from contact 118 goes to a bell or other alarm signal 136. The wire 124 connected with contact 123 goes to one of the terminals of the electromagnet 70 85 135. The wire 132 connected to contact 131 goes to the opposite terminal of the electromagnet 86. The other terminals of the two electromagnets 85—86 are connected to a terminal 137. The wire 135, which, as has 80 been explained, is connected with both levers 114—126, goes to one of the terminals of an electric battery 138, or other source of electric current, the other terminal of such battery being connected by a wire 139 with the terminal 137, and through it with opposite terminals of the two electromagnets. By following the diagram on Fig. 2, it will readily be apparent how records are made when the lock is operated. Assuming that 90 the door is unlocked, the parts will be in the position shown in Fig. 2, at which time no current will flow through either of the electromagnets 85—86, and consequently the cylinder 36 will rotate without having any 95 record made upon it. So long as the door remains unlocked the latch-bolt may be operated in the usual way in opening and shutting the door without making any record, because such operation will not affect any 100 of the electric switch mechanisms, since the arm 113 may swing freely without rocking the lever 126. When, however, the key-bolt is projected to lock the door, its movement into its opening in the keeper-plate 99 will 105 swing the plate 101 so as to rock its pivot 104 and swing the arm 107 to the right of the position shown in Fig. 11. This will rock bell-crank lever 114 and cause its lip 121 to make passing contact with the brush 110 123. This contact is only momentary, because said lip immediately passes beyond the engaging portion of said brush, which is made angular so as to secure such momentary contact. While this contact exists, a 115 closed circuit is established through electromagnet 85 by wires 124, 139, battery 138, wire 134, and lever 114. Said magnet is therefore energized and operates its type lever to make a record on the record sheet. 120 This movement of the lever 114 swings its arm 120 to the left, thereby permitting lever 126 to move into operative relation to arm 113, which is actuated by the cover-plate 108 of the latch-bolt opening. Consequently, whenever the latch-bolt is moved it rocks the lever 126 so as to move its arm 130 into passing contact with brush 131, which is also so shaped as to make the contact a momentary one. Whenever such con- 125 130

tact is made, a circuit is established through electromagnet 86 by wires 132, 139, battery 138, wire 135, connection 134, and lever 126. This energizes said electromagnet and operates the other type lever 69 to make a record on the record sheet. The characters of the two type levers being different, the record sheet shows separately the operations of the key-bolt and the latch-bolt, so that 5 the proprietor can tell which of them was operated, and at what time. When the key-bolt is withdrawn to unlock the door, a record is made by the type lever 68 in the same way as before, and the latch-bolt is accordingly disconnected from the record mechanism. It is therefore impossible to lock or unlock the door without making a record, and, so long as the door remains locked, every time it is tried by turning the knob 10 to operate the latch a record is made. The apparatus therefore is well adapted to serve the purpose of a watchman's time recorder, as such a watchman is usually required to try the doors on his beat at stated intervals, 15 and the apparatus described would properly record whenever that was done.

In Figs. 15 to 17 I have shown a modified construction, which, among other things, provides for assembling the parts with the 20 cover-plates of the key-bolt and latch-bolt openings at any desired distance apart to accommodate different styles of locks. The operation of the apparatus is, however, the same as that shown in Figs. 10 and 11. In 25 the construction shown in Figs. 15, 16, and 17, one end of each of the pivots 104 and 111 is mounted in a plate 154 which is secured to the keeper-plate 99,—the opposite ends of said pivots extending through the plates 106 30 in the way hereinbefore described. The plates 101—108 covering the openings in the key-bolt and the latch-bolt, respectively, may be spaced apart any desired distance to accommodate such openings by boring the 35 plates 154 and 106 at the proper points to receive the pivot 111. In order to permit this variation without changing the switch mechanism by which the various circuits are made, such switch mechanism is made as 40 follows: The pivot 104 is provided with a segmental rack 155, shown in Fig. 16, which meshes with a segmental rack 156, which 45 performs some of the functions of the lever 114. The rack 156 is mounted on a pivot 157, and is provided with a lug 158 and 50 with a cam-like projection 159. The lug 158 is adapted to make a passing contact with an arm 160 pivoted at 161 and normally pressed down against the stop 162 by 55 a spring 163, which is connected with a short arm 164 carried by said arm 160. This arm 160 corresponds with the spring-contact 123 shown in Fig. 11, and performs the same functions. The shoulder 159 is adapted 60 to engage one arm 165 of a bell-crank

lever 166, pivoted at 167 and having a downwardly-projecting arm 168. Connected to the latter arm is a spring 169 which tends to draw said arm to the left against a stop 170. This bell-crank lever 166 is connected with 70 wire 119 leading to bell 136, and so performs the functions of the spring-contact 118. The arm 168 is provided with a block of insulating material 171, which is interposed between it and the upper arm 172 of a lever 75 173 pivoted at 174. The lower arm 175 of said lever is provided with a lug 176 which serves as a contact projection. The arm 172 is normally held in the position shown in Fig. 16, when the door is unlocked, by 80 the spring 169 and a lighter spring 177, which is connected to a lug 178 on said lever. The spring 169, being stronger than the spring 177, normally holds the arm 168 in contact with its stop 170 and prevents the 85 arm 172 of the lever 173 from swinging to the right beyond the point where it is intercepted by the insulating block 171. When, however, the door is locked, the segmental rack 155 is swung to the right, oppositely 90 rotating rack 156 so that shoulder 159 strikes the arm 165 of the bell-crank lever 166 and swings arm 168 of said lever to the right, thereby permitting spring 177 to rock lever 173, carrying the lower arm 175 to 95 the left into contact with the stop 179. This carries the contact projection 176 over far enough so that it is in position to be intercepted by a lug 180 carried by a rack 181, mounted to slide longitudinally upon the 100 inner face of the plate 106, said rack being mounted upon pins 182 for that purpose. The rack 181 meshes with a segmental rack 183 mounted on the pivot 111, so that it is 105 swung by the swinging of the latch-bolt cover-plate 108. It will be apparent that when the door is locked, movement of the latch-bolt will move the rack 181 vertically so that its lug 180 makes a momentary passing contact with projection 176, and thereby 110 effects a registration in the manner already described, since the lever 173 performs the same functions as spring-contact 131. Obviously, the position of the pivot 111 may be varied vertically to a considerable extent, without affecting the operation of the 115 rack 181, by means of the segmental rack 183, and consequently the opening for the latch bolt may be so placed as to accommodate a great variety of locks without changing the construction of the operating parts carried by the keeper-plate. It will be understood that the several parts are insulated where necessary to provide the circuits illustrated in Fig. 2.

The alarm mechanism.—In Fig. 2 I have shown diagrammatically the manner in which bolts, or other securing devices applied to openings other than the main door, are connected up with the other parts of 130

the apparatus so that when the main door is locked, if such openings have not been secured an alarm is given. In said figure, I have shown the connections of two of 5 such supplemental locks. Referring to said figure, 140 indicates a switch member, preferably in the form of a lever, pivoted at 141 and adapted to make contact with a spring 142 connected by a wire 143 to a 10 wire 144, which leads to that terminal of the bell 136 which is not connected to wire 119. The lever 140 is connected by wire 145 to a wire 146 which connects with wire 139. It will be apparent that when the lever 140 15 is in contact with the spring 142, there is an unbroken connection from spring-brush 118, through the bell, to one terminal of the battery 138. The circuit through the battery and bell is, however, not closed unless arm 20 116 of lever 114 is in contact with the spring 118, which occurs only when the main door is locked, as has been described. It follows that when the door is not locked, the bell 136 does not sound, even if the lever 140 is 25 in contact with spring 142, but if the door has been locked and the lever 140 is in contact with spring 142, there will then be a closed circuit through the battery and bell, causing the bell to ring. In the same figure 30 I have illustrated another lever 147, similar to the lever 140, which coöperates with a spring 148, said lever being connected to wire 146, while the spring 148 is connected to wire 144. It will be apparent from the 35 illustration that however many switches similar to the levers 140 and 147 may be used, if only one of them is in contact with its spring, the bell will ring, but if all of them are disconnected from their respective 40 springs, the bell will not ring when the main door is locked. The illustration in Fig. 2 is mainly diagrammatic, but it will be readily understood that in applying the supplemental locks or bolts to openings 45 other than the main door it is necessary only to provide fastening means which will open an electric switch when fastened, and will close it when they are unfastened, in order to secure the results described. A 50 convenient device for this purpose is shown in Figs. 13 and 14. As therein shown, 149 indicates an ordinary bolt mounted in a fixture 150 in the usual way. This bolt is applied to the movable part of the opening, 55 such as a door, or a window sash. Coöperating with the bolt 149 is a pin 151, mounted in a suitable bracket 152 which is secured to a stationary part of the opening in such position that the pin 151 alines with 60 the bolt 149. A spring 153 normally presses said pin toward the bolt, its movement being limited by a stop in any suitable way. One of the switch levers, as 140, is mounted on the bracket 152 and connected with the pin 65 151 in such manner that when said pin 151

is moved back so as to compress the spring 153 it rocks the switch lever 140 and moves it out of contact with its spring 142, which is shown as being mounted on the bracket 152. The bracket 152 acts as a keeper for 70 the bolt 149 when it is in locking position, and consequently, when said bolt is shot to secure the window, or other part to which it is attached, it moves the pin 151 to the right, thereby disconnecting the lever 140 from the 75 spring 142 and opening the circuit at that point. In the construction shown, the bolt is arranged to be secured in its projected position by a notch in the usual way, to prevent the spring 153 from moving the bolt 80 back out of locking position.

By means of the apparatus described, it will be seen that when the main door is closed for the night and locked, if the bell 136 rings, it indicates that there is some 85 other opening that has not been properly secured; or if, after the store is locked, any such other opening should be opened, the bell will ring, giving the alarm. The operation of the latch-bolt while the door is 90 locked has no effect on the bell.

From the foregoing description it will be apparent that the construction described provides for operating two signaling devices by the movement of a lock-bolt, which may 95 be either the key-operated bolt or the usual latch-bolt, one of such signaling devices being invariably operated to record the time of such movement of the key-bolt, and, while the door remains locked, to record the time 100 of movement of the latch-bolt, while the other of such signaling devices sounds an alarm when the key-bolt alone is operated to lock the door, provided all other fastening devices in the alarm signal circuit have not 105 previously been secured.

The terms "signal" and "signaling devices" are herein used in a generic sense to indicate the recording devices or equivalent mechanism of any suitable description, the 110 operation of which is controlled by movement of the bolt or bolts of the lock, and the term "door lock" is intended to include not only a lock for doors, but also locks employed in any equivalent situation.

What I claim as my invention, and desire to secure by Letters Patent, is,—

1. A signaling apparatus comprising an electrically operated signal, a lock having a movable bolt, and means separate from the lock adapted to be operated by said bolt when the same is projected or retracted to momentarily actuate said signal.

2. A signaling apparatus comprising an electrically operated recording apparatus, a lock having a movable bolt, and means separate from the lock adapted to be operated by said bolt when the same is projected or retracted to momentarily actuate said recording apparatus.

3. A signaling apparatus, comprising an electrically-operated signal, a lock having a movable key-operated bolt, and means mounted on a stationary support separate from the lock and adapted to be operated by said bolt when the same is moved in either direction, to momentarily actuate said signal. 65
4. A signaling apparatus, comprising an electrically-operated recording apparatus, a lock having a movable key-operated bolt, and means mounted on a stationary support separate from the lock and adapted to be operated by said bolt when the same is moved in either direction, to momentarily actuate said recording apparatus. 70
5. A signaling apparatus for door locks, comprising an electrically operated signal, a lock carried by the door, having a movable key-operated bolt, and means mounted on the door-frame and adapted to be operated by said bolt when the same is projected or retracted to momentarily actuate said signal. 75
6. A signaling apparatus for door locks, comprising electrically operated signal mechanism, a lock carried by the door, having a plurality of movable bolts, and means mounted on the door-frame and adapted to be operated by the retraction of either of said bolts when both shall have been projected to actuate said signal mechanism. 80
7. A signaling apparatus for door locks, comprising an electrically-operated recording apparatus, an electrically-operated alarm signal, a lock carried by the door having a movable bolt, and means mounted on the door frame and adapted to be operated by said bolt when the same is moved for momentarily actuating said recording apparatus and completing an operating circuit to said alarm signal. 85
8. A signaling apparatus for door locks, comprising an electrically-operated signal, a lock carried by the door, having a movable bolt, a keeper carried by the door frame having an opening to receive said bolt, a movable member adapted to be interposed in said opening and to be moved by the projection or retraction of said bolt, and means operated by movement of said member for momentarily actuating said signal. 90
9. A signaling apparatus, comprising an electrically-operated recording apparatus, an electrically-operated alarm signal, a lock having a movable key operated bolt, means mounted on a stationary support separate from the lock and adapted to be operated by projection of the lock-bolt, for operatively establishing an operating circuit through said alarm signal and momentarily actuating said recording apparatus, a latch-bolt, and means operated by movement of said latch-bolt only while said lock-bolt is projected for actuating said recording apparatus. 95
10. A signaling apparatus, comprising an electrically-operated recording apparatus, a lock having a plurality of bolts, means operated by projection of one of said bolts for operating said recording apparatus, and means operated by movement of the other bolt only while said first-mentioned bolt remains projected, for operating said recording apparatus. 100
11. A signaling apparatus, comprising a plurality of electrically operated recording devices, a lock having a plurality of bolts, means operated by projection of one of said bolts for operating one of said recording devices, and means operated by movement of the other bolt only while said first-mentioned bolt remains projected for operating the other of said recording devices. 105
12. A signaling apparatus, comprising an electrically-operated recording apparatus, a lock having a key-bolt and a latch-bolt, means operated by projection of the key-bolt for operating said recording apparatus, and means operated by movement of the latch-bolt only while the key-bolt remains projected, for operating said recording apparatus. 110
13. A signaling apparatus, comprising an electrically-operated recording apparatus, an electrically-operated alarm signal, a lock having a key-bolt and a latch-bolt, means operated by projection of the key-bolt for operating said recording apparatus and said alarm signal, and means operated by the latch-bolt while the key-bolt remains projected, for operating said recording apparatus. 115
14. A signaling apparatus, comprising an electrically-operated recording apparatus, an electrically-operated alarm signal, a lock having a key-bolt and a latch-bolt, means operated by projection of the key-bolt for operating said recording apparatus and said alarm signal, and means operated by the latch-bolt while the key-bolt remains projected, for operating said recording apparatus, said latch-bolt being operable independently of said alarm signal. 120
15. A signal apparatus, comprising an electrically-operated recording apparatus, an electrically-operated alarm signal, a lock having a key-bolt and a latch-bolt, means operated by movement of the key-bolt for operating said recording apparatus and completing an operating circuit through said alarm signal, and means operated by movement of the latch-bolt only while the key-bolt remains projected, for operating said recording apparatus. 125
16. A signaling apparatus, comprising an electrically-operated recording apparatus, an electrically-operated alarm signal, a lock

- having a key-bolt and a latch-bolt, means 65
operated by movement of the key-bolt for
operating said recording apparatus and
completing an operating circuit through
5 said alarm signal, and means operated by
movement of the latch-bolt only while the
key-bolt remains projected, for operating
said recording apparatus, said latch-bolt
being operable independently of said alarm
10 signal.
17. A signaling apparatus, comprising an
electrically-operated recording apparatus,
an electrically-operated alarm signal, a lock
having a key-bolt and a latch-bolt, means op- 70
erated by projection of the key-bolt for op-
erating said recording apparatus and said
alarm signal, means operated by the latch-
bolt while the key-bolt remains projected,
20 for operating said recording apparatus, and
means in the alarm signal circuit adapted to
be operated to prevent the actuation of said
alarm signal by said key-bolt.
18. A signaling apparatus, comprising an
electrically-operated recording apparatus,
25 an electrically-operated alarm signal, a lock
having a key-bolt and a latch-bolt, means op-
erated by movement of the key-bolt for op-
erating said recording apparatus and com-
pleting an operating circuit through said
30 alarm signal, means operated by movement
of the latch-bolt only while the key-bolt re-
mains projected, for operating said record-
ing apparatus, and means in the alarm sig-
nal circuit adapted to be operated to prevent
35 the actuation of said alarm signal by said
key-bolt.
19. A signaling apparatus for door locks,
comprising an electrically-operated signal,
a lock carried by the door and having a key-
40 bolt and a second bolt, and actuating means
carried by the door frame and actuated by
movement of said key-bolt for operating
said signal, and also actuated by movement
of said second-bolt only, while said key-bolt
45 is projected, to operate said signal.
20. A signaling apparatus, comprising an
electrically-operated recording apparatus, a
lock having a key-bolt and a latch-bolt, and
actuating means actuated by movement of
50 said key-bolt for operating said recording
apparatus, and also actuated by movement
of said latch-bolt while said key-bolt is
projected, to operate said recording appa-
ratus.
- 55 21. A signaling apparatus for door locks,
comprising an electrically-operated signal,
a lock carried by the door and having a key-
bolt and a latch-bolt, an actuating device
carried by the door frame and operated by
60 said latch-bolt for momentarily actuating
said signal, said actuating device being nor-
mally disconnected from said signal, and
means operated by the key-bolt, for connect-
ing said actuating device with the signal.
22. A signaling apparatus for door locks, 65
comprising an electrically-operated record-
ing apparatus, a lock carried by the door
and having a key-bolt and a second bolt, an
actuating device mounted on the door frame
and operated by said second-bolt for actuat- 70
ing said recording apparatus, said actuating
device being normally disconnected from
said recording apparatus, and means oper-
ated by movement of the key-bolt, for con-
necting said actuating device with the re- 75
cording apparatus.
23. A signaling apparatus, comprising an
electrically-operated recording apparatus
having two record making members, a lock
having a key-bolt and a latch-bolt, and ac- 80
tuating devices associated, respectively, with
said record making members and adapted
to be operated, respectively, by said key-
bolt and said latch-bolt to actuate the ap-
propriate record making member, the ac- 85
tuating device associated with said latch-
bolt being operative only while the key-bolt
remains projected.
24. A signaling apparatus, comprising an
electrically-operated recording apparatus 90
having two record making members, a lock
having a key-bolt and a latch-bolt, actuating
devices associated, respectively, with
said record making members and adapted
to be operated, respectively, by movement 95
in either direction of said key-bolt and said
latch-bolt, the actuating device operated by
the latch-bolt being normally inoperative,
and means operated by the projection of the
key-bolt, for making the latter actuating 100
device operative.
25. The combination with a lock adapted
to be mounted on a movable member and
having a lock-bolt, of a keeper adapted to
be mounted on a stationary support, an 105
electrically-operated signal, and means asso-
ciated with the keeper and operated by
movement of the lock-bolt into or out of
said keeper, for momentarily actuating said
signal.
26. The combination with a lock adapted
to be mounted on a movable member and
having a lock-bolt, of a keeper adapted to
be mounted on a stationary support, an elec- 115
trically-operated recording apparatus, and
means associated with the keeper and oper-
ated by movement of the lock-bolt into or
out of said keeper, for momentarily actuat-
ing said recording apparatus.
27. The combination with a lock adapted 120
to be mounted upon a movable support and
having a key-bolt and a latch-bolt, of a
keeper adapted to be mounted on a station-
ary support, an electrically-operated signal,
means with the keeper and operated by 125
movement of the key-bolt into or out of
said keeper, for actuating said signal, and
means associated with the keeper and op-

- erated by movement of the latch-bolt only while the key-bolt remains projected, for actuating the signal.
28. The combination with a lock adapted to be mounted upon a movable support and having a key-bolt and a latch-bolt, of a keeper adapted to be mounted on a stationary support, an electrically-operated recording apparatus, means operated by movement of the key-bolt into or out of said keeper for actuating said recording apparatus, and means operated by movement of the latch-bolt in said keeper only while the key-bolt remains projected, for actuating the recording apparatus.
29. The combination with a lock adapted to be mounted in a movable support and having a key-bolt and a latch-bolt, of a keeper adapted to be mounted on a stationary support, an electrically-operated recording apparatus having record making devices appropriated, respectively, to said key-bolt and said latch-bolt, means operated by movement of the key-bolt into or out of said keeper to operate the record making device appropriated thereto, and means operated by movement of the latch-bolt in said keeper only while the key-bolt remains projected, to operate the record making device appropriated to said latch-bolt.
30. The combination with a door having a lock provided with a key-bolt and a latch-bolt, of electrically-operated chronographic apparatus, and means for actuating said chronographic apparatus to indicate the time when said key-bolt is projected or retracted to lock or unlock the door, and when said latch-bolt is actuated only while the key-bolt remains projected.
31. The combination of a recording apparatus comprising a platen, a plurality of record making devices adapted to coöperate with said platen to make records, electrically-operated mechanism for actuating said record making devices independently of each other, and members associated respectively with different record making devices and adapted to be actuated to separately operate their respective record making devices, one of said members being normally inoperative and being made operative by the actuation of the other member.
32. The combination of a recording apparatus comprising a platen, chronometric mechanism for controlling the operation of said platen, a plurality of record making devices adapted to coöperate with said platen to make records, electrically-operated mechanism for actuating said record making devices independently of each other, and members associated respectively with different record making devices and adapted to be actuated to separately operate their respective record making devices, one of said members being normally inoperative and being made operative by the actuation of the other member.
33. The combination with a chronographic apparatus, comprising means adapted to be operated to make a record, of a keeper-plate having an opening for the admission of a lock-bolt, and mechanism associated with said keeper-plate and operated by movement of a lock-bolt in said opening for actuating said chronographic apparatus.
34. The combination of a recording apparatus comprising two record making members, a keeper-plate arranged to receive the key-bolt and the latch-bolt of a lock, means associated with said keeper-plate and operated by movement of a key-bolt in said keeper-plate for actuating one of said record making members, and means actuated by movement of a latch-bolt in said keeper-plate only while the key-bolt is in said keeper-plate, for actuating the other record making member.
35. The combination of a recording apparatus comprising a spirally-moving cylinder, chronometric mechanism for moving said cylinder, an electrically-operated record making member adapted to be actuated to make a record on a record sheet mounted on said cylinder, and means adapted to be operated by the projection or retraction of a lock-bolt for momentarily actuating said record making member.
36. The combination of a recording apparatus comprising a spirally-moving cylinder, chronometric mechanism for moving said cylinder, a record making member adapted to be actuated to make a record on a record sheet mounted on said cylinder, means adapted to be operated by a key-bolt for actuating said record making member, a second record making member also coöperating with said cylinder, and means adapted to be operated by the latch-bolt of a lock for actuating said second record making member.
37. The combination of a recording apparatus comprising a spirally-moving cylinder, chronometric mechanism for moving said cylinder, a record making member adapted to be actuated to make a record on a record sheet mounted on said cylinder, means adapted to be operated by a key-bolt for actuating said record making member, a second record making member also coöperating with said cylinder, means adapted to be operated by the latch-bolt of a lock for actuating said second record making member, and means for normally disconnecting the latch-bolt actuating mechanism from the recording apparatus, and for automatically connecting it therewith while the key-bolt remains projected.
38. A recording apparatus, comprising a

- suitable support, a screw-threaded shaft pivotally connected with said support and adapted to be swung laterally, means for securing said shaft in a vertical position, a 5 cylinder rotatably mounted upon said shaft and movable longitudinally on the threads thereof, said cylinder being movable laterally with said shaft, means independent of said cylinder for making a record thereof, a 10 chronometer, and means for detachably connecting said cylinder with said chronometer.
39. A recording apparatus, comprising a suitable support, a screw-threaded shaft connected with said support, a cylinder rotatably mounted upon said shaft and movable longitudinally thereof, means carried by said cylinder and operable independently of longitudinal movement thereof for detachably engaging the threads of said shaft, a 15 chronometer, and means for detachably connecting said cylinder with said chronometer.
40. A recording apparatus, comprising a suitable support, a screw-threaded shaft pivotally connected with said support and adapted to be swung laterally into a substantially horizontal position, means for securing said shaft in a vertical position, a cylinder rotatably mounted upon said shaft and movable longitudinally on the threads 20 thereof, said cylinder being movable laterally with said shafts, means for making a record on said cylinder, a chronometer, means for detachably connecting said cylinder with said chronometer, and means for holding said shaft in a substantially horizontal position.
41. The combination of a door having a lock provided with a plurality of bolts, of electrically-operated chronographic apparatus, and means for actuating said chronographic apparatus to indicate the time when one of said bolts is projected or retracted, and when the other of said bolts is retracted only while said first-mentioned bolt remains 45 projected.
42. The combination with a chronographic apparatus, comprising electrically-operated means adapted to be operated to make a record, of a keeper plate having an opening for the admission of a bolt, and mechanism associated with said keeper plate and operated by movement of said bolt in said opening for actuating said chronographic apparatus.
43. A recording apparatus, comprising a 50 base, a chronometer mounted thereon, a standard rising from said base, a screw-threaded shaft pivotally supported at its upper end by said standard in alinement with the axis of said chronometer, a cylinder mounted upon said shaft and movable spirally thereon, means for connecting said cylinder with the chronometer, whereby said cylinder is regularly rotated by said chronometer, and means for securing said shaft in either a vertical or a substantially horizontal position.
44. A recording apparatus, comprising a base, a chronometer mounted thereon, a standard rising from said base, a screw-threaded shaft supported at its upper end by said standard in alinement with the axis of said chronometer, a cylinder mounted upon said shaft and movable spirally thereon, and a rod movable longitudinally through said cylinder and engaging one of the hands of the chronometer for operatively connecting said cylinder with the chronometer, meanwhile permitting vertical movement of the cylinder.
45. A recording apparatus, comprising a standard, a spirally-threaded shaft depending from said standard, a cylinder mounted on said shaft, a chronometer for actuating said cylinder, a pair of oppositely-disposed type levers supported by said standard and adapted to be operated to strike said cylinder through an opening in said standard, a plurality of bolts adapted to be projected or retracted, and electrically-actuated devices actuated separately by movement of one or the other of said bolts for operating said type levers respectively.
46. A recording apparatus, comprising a base, a chronometer mounted on said base, a standard rising from said base, a shaft supported by said standard in alinement with the axis of the hour hand of the chronometer, a cylinder mounted upon said shaft and movable spirally thereon, means connecting said cylinder with the chronometer, record making devices coöperating with said cylinder to make records thereof, and a movable stop mounted on the standard and adapted to be adjusted to determine the position of the cylinder upon its shaft.
